ACETYLENE BURNING IRON

Joseph L. Roberts, Jamaica, N. Y., assignor of
one-half to Henry J. McCarthy, Baltimore, Md.

Application August 18, 1931, Serial No. 557,899

5 Claims. (Cl. 158—14)

This invention relates to an acetylene burning iron.

In branding live stock in stock yards and horses in racing stables or the like and in performing 5 certain surgical operations on animals, it is necessary to have a tip shaped to perform the desired work, which is heated to a white heat. In performing this operation in stock yards and stables, it is extremely dangerous and generally 10 against the rules to have an exposed flame which might set fire to straw and the like found in large quantities in such places. Furthermore, if the flame is exposed in the vicinity of the branding tip, a sharply defined brand cannot be 15 produced for the hair and skin surrounding the brand will be unintentionally burnt.

It therefore is the primary object of this invention to provide an acetylene burning iron which will heat a working head or tip to a white heat by means of a highly concentrated and unexposed flame.

A further object of the invention is to provide an acetylene burning iron which performs its intended work in a very efficient manner and 25 which is constructed of comparatively few parts, cheaply and conveniently assembled to permit of easy manipulation and repair.

Other objects and advantages of the invention will be apparent during a course of the following description.

Fig. 1 is a side elevational view of the acetylene burning iron embodying this invention;

Fig. 2 is a detail enlarged longitudinal sectional view partly broken away of the handle portion, the adjacent stem portion and the outer end portion of the iron and including the combustion chamber and burning tool;

Fig. 3 is a transverse sectional view taken upon line 3—3 of Fig. 2; and

Fig. 4 is a transverse sectional view taken upon line 4—4 of Fig. 2.

In the drawing, wherein, for the purpose of illustration, is shown a preferred embodiment of this invention, the numeral 6 designates in its entirety the handle portion of the tool which includes a tubular metal core 7 having formed at one end a nipple 8 to which a flexible pipe or the like 9 may be connected for supplying the iron with acetylene gas. The remaining end of the 45 core 7 has an enlarged socket 10 formed thereon which is internally screw threaded at 11 and is formed with a flared outer edge portion 12. The bore of the core in the vicinity of the socket 10 is reduced in diameter, as at 13, to form a Venturi 50 passage. An insulating grip 14 is suitably posi-

tioned upon the core 7. The front end of the grip 14 has suitably secured thereto a shield plate 15 which is intended to prevent the hand of the operator from accidentally moving beyond the end of the grip.

A stem 16 is designed to be connected to the forward end of the handle portion 6 and for this purpose includes an externally threaded shank 17 which is detachably threaded into the bore of the socket 10. This shank portion 17 is formed 10 with a circular series of radially opening, air inlet ports 18 which are positioned in radial alignment with the flared outer edge 12 of the socket 10. Adjacent the threaded shank 17 of the stem 16, an enlarged tool engaging, polygonal portion 19 is provided on the stem. It will be noted that the inner end face of this enlarged portion 19 is spaced from the extremity of the flared edge 12 to provide an inlet for air to the ports 18 by way of the bore of the enlarged edge 12. Removably threaded within the shank portion 17 is an apertured disc 20 which controls the volume of gas permitted to pass into the stem 16. It is to be understood that discs having different sized apertures may be provided for permitting 25 different volumes of gas to be supplied to the working end of the iron.

The outer end of the stem 16 has suitably connected thereto an elbow 21 to which is connected one end of a tubular combustion chamber 22. 30 This combustion chamber has formed in its bore a restricted, internally threaded portion 23 and two axially spaced inwardly projecting annular ribs 24 and 25. It will be noted that the rib 24 is spaced axially from the reduced threaded portion 23 a sufficient distance to form an annular chamber or groove 26 while the remaining annular rib 25 is located at the outer end of the combustion chamber 22 to constrict said end.

The burning tool, designated in its entirety 40 by the reference character 27, is formed with a head 28 having the desired burning surface 29 which may take the form of one or more characters for branding purposes or different shapes suitable for surgical operations, principally performed by veterinarians. This head 28 is provided with a rearwardly extending flange 30 which is formed with an outwardly flaring inner wall 30a. Projecting axially from the burning tool 27 is a shank 31 having a threaded extremity 32 by 50 means of which the tool may be connected to the internally threaded reduced portion 23 formed in the combustion chamber 22. It will be noted that the shank 31 is positioned within the combustion chamber and extends axially there- 55

through for substantially the entire length of the chamber. The diameter of the shank 31 is less than the internal diameter of the ribs 24 and 25 and cooperates with these ribs and the bore of the combustion chamber to form an annular space extending longitudinally around the shank 31.

5 The shank is formed with a pocket 34 at its inner end which communicates with the bore of the stem 16 to receive the gas from said stem. 10 The wall of the pocket 34 is provided with a plurality of radially opening ports 35 for establishing communication between the pocket 34 and the annular groove or pocket 26 formed within the chamber 22 by the rib 24 and the threaded 15 portion 23.

15 The operation of this burning tool is as follows: Acetylene gas supplied to the handle portion by the tube 9 will flow through the said handle portion and into the stem 16 where it will be mixed 20 with air entering through the inlet ports 18. The gas will flow from the stem 16 into the elbow 21 and from the elbow into the pocket 34 of the tool shank 31. The gas will leave the pocket 34 by way of the ports 35 and will flow from the groove 25 26 in the chamber axially through the latter to be discharged from the outer restricted end 25 of the chamber. The gas leaving this outer end of the chamber will, of course, be ignited and the flame which, due to the use of acetylene gas, will 30 be a short blue flame, will be discharged into the confining groove or pocket formed in the head of the tool between the wall 38a of the flange 30 and the exterior of the shank. This short blue flame will be entirely consumed within this annular groove and will concentrate its heat at the bottom of the groove for raising the temperature of the active surface 29 of the head to the desired white heat. The flame will not escape from the 35 annular groove formed in the head 28 and will not be exposed in a manner which will produce a fire hazard if used around inflammable materials. Due to the confining of the flame within the annular groove formed in the head of the tool, it will be impossible to burn the hair or skin 40 surrounding the character branded on an animal with the result that a very sharply defined brand will be produced.

45 It is to be understood that the form of this invention herewith shown and described is to be taken as a preferred example of the same, and that various changes in the shape, size and arrangement of parts may be resorted to without departing from the spirit of the invention or the scope of the subjoined claims.

50 Having thus described the invention, I claim:

1. In an acetylene burning iron, a tubular handle, a tubular stem carried by the handle, an air supply inlet in the stem, a tubular combustion chamber in communication with said stem, said chamber having formed therein a threaded reduced portion and two inwardly directed annular ribs, one of said ribs being spaced axially of the threaded portion to form in the chamber an annular groove and the other rib being formed at 55 the other edge of the chamber to constrict the

same, and a burning tool having a shank of less diameter than the diameter of the combustion chamber at said ribs inserted in the chamber to be connected to the said threaded portion, said shank having a pocket formed therein in communication with the bore of the stem and with ports through the wall of the pocket to connect the latter with said annular groove. 5

2. In an acetylene burning iron, a tubular handle, a tubular stem carried by the handle, an air supply inlet in the stem, a tubular combustion chamber in communication with said stem, said chamber having formed therein a threaded reduced portion and two inwardly directed annular ribs, one of said ribs being spaced axially of the threaded portion to form in the chamber an annular groove and the other rib being formed at the other edge of the chamber to constrict the same, and a burning tool having a shank of less diameter than the diameter of the combustion chamber at said ribs inserted in the chamber to be connected to the said threaded portion, and a head to be positioned beyond the end of the chamber, said shank having a pocket formed therein in communication with the bore of the stem and with ports through the wall of the pocket to connect the latter with said annular groove, said head having a rearwardly directed flange forming an annular flame confining pocket to receive the flame discharged from the constricted end of the combustion chamber. 30

3. In an acetylene burning iron, a tubular handle, a tubular stem carried by the handle, an air supply inlet in the stem, a tubular combustion chamber in connection with the stem, said combustion chamber having a rib formed at the outlet end portion of the same to constrict the flame, and a burning tool having a head formed with a rearwardly opening flame confining groove and a shank mounted within the combustion chamber of less diameter than the opening formed by the rib, said groove of the head being spaced from and opposed to the outer end of the combustion chamber. 35

4. In an acetylene burning iron, a tubular body, a tubular stem carried by the body, an air supply inlet for the stem, an annular combustion chamber connected to the stem, said combustion chamber including means for confining and directing the flame, and a burning tool having a head formed with a rearwardly opening flame confining groove supported at the outer end of the combustion chamber with the groove positioned to receive the flame from the chamber. 50

5. In an acetylene burning iron, a burning tool having a head formed with a sharply defined flame confining groove opening rearwardly of the head, a cylindrical member having an imperforate wall, and a shank carried by said head received in said cylindrical member forming therewith an annular combustion chamber, said combustion chamber directing the flame against said head and into said groove. 55

JOSEPH L. ROBERTS.
